COMBINED SCREEN FRAME AND WEATHER STRIPPING

Harry W. Thomas, Miami Beach, Fla., assignor to Radio Patents Corporation, New York, N. Y., a corporation of New York

Application March 4, 1944, Serial No. 524,999

13 Claims. (Cl. 160—40)

My invention relates to a combined screen frame and weather stripping for casement windows suited particularly, though not limitatively, for screens made of nylon or other ductile synthetic material.

Screening made of nylon or equivalent synthetic resinous and other ductile materials are liable to be cut or sheared when forcefully clamped or squeezed between hard surfaces such as a window sash and metal frame or when mounted to a metal screen frame by forcing a metal spline to wedge the screen into the frame, as is common in the mounting of metal wire screens.

Moreover, theoretically, the conventional rigid metal frame screens are supposed to fit tightly against the window sash. However, in practice such an ideal condition is not always obtainable. The screen frame may be slightly warped or the window member may not have a true plane. Accordingly, therefore, the screen frame remains ajar along portions of the crack perimeter sufficient to allow insects to come through and resulting in other disadvantages and defects well known.

Accordingly, an object of the present invention is to provide a novel screen frame construction which is simple in design and easy to install and which will insure a complete and efficient seal bridging the entire perimeter between the screen and sash members.

Leaking steel casement windows are particularly a problem where heavy rainstorms are frequent and severe and for this reason many types of spring metal weather stripping for casement windows have been developed in the past, all of which have proven expensive to install and unsatisfactory in various respects. These weather stripping elements are designed to actuate between the sash and frame sections of the windows, and among other defects, are subject to develop hinge bind and to destroy the weather contact between the outer legs of the Z-bar sash members.

Accordingly, another object of the invention is to provide an improved weather stripping for casement windows arranged to cooperate with both the sash and frame sections of the window in such a manner as to effect an efficient weathering seal of the entire crack perimeter between said frame and sash sections.

Another object is to provide a combined resilient screen holder and weather stripping for casement windows adapted to insure a close and perfect fit along the entire screen perimeter and

at the same time to cooperate with both the sash and frame sections to insure an efficient weather seal therebetween.

The above and further objects and novel aspects of my invention will become more apparent from the following detailed description taken in reference to the accompanying drawings forming part of this specification and wherein:

Figure 1 is a perspective view showing the novel screen frame secured to a standard casement window frame as seen from the inside of the building.

Figure 2 is an enlarged sectional view showing one form of a combined screen frame and weather stripping according to the invention and taken on line 2—2 of Figure 1, omitting fastenings and operating means.

Figure 3 is an enlarged fragmentary perspective view similar to Figure 1 and cut along the line 3—3.

Figure 4 shows a cross-section of the weathering element and resilient screen holder embodied in Figures 1 to 3.

Figure 5 is a partial cross-sectional view similar to Figure 2 and showing a modification of the invention.

Figures 6 and 7 are detail views of the combined weathering strip and screen spline embodied in Figure 5 shown in partially and fully assembled position, respectively, and

Figure 8 is a cross-sectional view similar to Figure 5 and showing a further modification of the invention.

Like reference numerals identify like parts throughout the different views of the drawings.

As more particularly shown in Figures 1 to 3, the numeral 10 represents the frame section of a metallic casement window of any suitable construction known in the art, such as in the form of a Z-bar as shown in the example illustrated. Numeral 11 shows the sash or ventilator section of the window suitably hinged in a manner well known and formed either in a single section or a plurality of members and having secured thereto the glass plate 12. The ventilator is also shown of a Z-bar construction and seats against the outer face of the frame 10 in the close position of the windows shown in the drawings. The improved screen frame and weather stripping according to the invention is adapted for attachment to the inside of the window frame 10 in any suitable manner and is constructed as described in the following.

A rigid frame 13 of sufficient stiffness has side and cross-bars which may or may not be secured

at their junctions in any appropriate manner as by welding, rivets or the like. The individual frame members are preferably hollow as shown and are made of shaped suitable sheet material such as steel, aluminum alloy or any other suitable material and may be either integral or with their edges in abutting contact or secured together in any suitable manner. This frame is secured to the window frame 10 with a strip or member 14 of resilient material such as rubber or the like interposed therebetween in the manner shown in the drawings. This resilient member serves as a gasket to provide a tight seal or close contact throughout the entire perimeter of the screen 15 interposed and clamped between the member 14 and the frame 13. Due to the flexibility of the member 14 the perimeter of the screen will be secured tightly and without cracks to the window frame 10, while at the same time making it possible to use a screen of relatively soft or ductile material such as nylon or any other equivalent resinous synthetic or other ductile material without the danger of cutting or shearing the screen during the clamping operation.

If desired the resilient member 14 may be permanently secured to the frames 10 and 13 by gluing or cementing or in any other suitable manner as indicated at 14' to improve the effectiveness of the weather seal and to completely eliminate the possibility of cracks along the screen and frame perimeters to prevent the penetration of dust, air or water in the closed position or to exclude insects in the open position of the window.

In order to obtain a two-point weather seal by the member 14 pressing against or engaging both the frame and sash sections 10 and 11, respectively, member 14 is arranged to project sufficiently into the window area in such a manner as to contact the sash section 11 in the closed position as shown in the drawings and to insure a perfect and efficient two-point weather seal, whereby to completely eliminate dust, air or water from penetrating to the inside of the window.

In the example shown in the drawings, the screen frame 13 is mounted by means of brackets 16 secured to the frame 10 by screws or bolts or in any other suitable manner. Any other connection or mounting may be employed to suit special and existing requirements as is understood.

As pointed out above, the combined resilient screen holder and weathering strip 14 may consist of rubber, rubberized or any equivalent material possessing an adequate resiliency. In the example shown in Figures 1 to 4, it is made from a flat strip having its lengthwise edges reversely bent and secured to the strip by gluing or the like as shown in Figure 4 to provide a pair of adjacent loop shaped sections capable of being compressed so as to provide an efficient seal in the manner shown in Figure 2 in the assembled or operative position. If desirable, the loop engaging the sash 11 may be reinforced along its inner edge as shown at 17 to provide added stiffness and improve the weathering action.

The window is shown provided with a suitable operating mechanism 17' of any known construction for opening and closing the ventilator 11 from the inside in a manner well understood and known in the art.

Referring to Figures 5 to 7, I have shown a modified construction of a combined screen frame construction and weather stripping embodying

the principles of the invention. In this modification, the resilient screen spline and weathering member 20 is shaped to dovetail with the metal frame 13 secured to the frame section 10. For this purpose the cross-section of the resilient member 20 has a lower curved or vaulted surface followed by opposite lateral projections 22 and terminating in extensions or weathering elements engaging the frame 10 and vent section 11 of the window as shown in Figure 5. The rigid screen frame 13 is of channel-shaped cross-section and has an open inner side with its free edges reversely bent inwardly as shown at 23 and adapted to dovetail with the projections 22 of the resilient member 20 in the inserted position, whereby to firmly hold the spline 20 and interposed screen 15 within the frame 13.

During assembly, the end of the screen is placed over the metal frame 13 and the resilient spline 20 inserted in the frame in the manner shown in Figure 6, whereupon it may be forced into fully inserted position as shown in Figure 7 due to the resiliency of the member 20. When the latter is secured or clamped against the frame section 10 by means of the brackets 16 and screws 18, the outer extension 21 of the member 20 will be pressed against the inner edge of the Z-bar of frame 10 as shown in Figure 5, while the inner extension 21 of member 20 engages the inner Z-bar of the vent section 11 upon closing of the window. In this manner, there is obtained an efficient two-point weather seal engaging both the sash and frame sections of the window. At the same time, the member 20 provides an efficient seal along the perimeter of the screen 15 in the manner pointed out hereinabove.

The screen spline and weathering member 20 may be provided with a central metal core or wire 24 for stiffening purposes if desirable. The mitered corners of member 20 may or may not be joined as they will tend to squeeze together under pressure in the assembled or clamped position of the spline. The curved bottom shape of the spline 20 tends to greatly improve and ease the insertion into the metal frame 13. A simple tampering tool can be employed so as to simultaneously ram the spline in both sides of the metal frame. The screen is stretched taut when the resilient spline is forced into the metal frame and may be easily removed and replaced when it should become necessary to renew the screen. This screen mounting results in a tight seal of the screen perimeter, enabling both the use of relatively soft or ductile screen material such as nylon and at the same time excluding any possibility of cracks between the screen and mounting frame.

There is thus provided by the invention a combined screen frame and weather stripping for a casement window suited especially for screens made of relatively soft and ductile material and which effectively seals the perimeter of the screen without danger of cutting or shearing the screen material and at the same time provides an efficient weathering seal between the ventilator and frame sections to exclude wind, water or dust in the closed position of the window.

Referring to Figure 8 there is shown a further embodiment of the invention wherein the resilient weathering member 28 is provided with extensions engaging both the frame 10 and vent sections 11 in a manner similar to Figure 5, but is secured to the outside of the frame 13 by gluing or cementitious or in any other appropriate manner. Frame 13 is provided with an inner reentrant por-

tion adapted to receive a further resilient spline 26 of metal, rubber or the like for securing the screen 15 in the manner shown and readily understood from the drawings. This construction has the advantage that the screen may be removed or replaced without removing the weather stripping such as during the winter months. Further provisions may be made to replace the screen by a storm sash of known construction within the scope of this invention.

As is evident, the combined weather stripping and resilient screen holder disclosed and described herein may be modified in various manners within the broader scope and spirit of the invention. Thus, the rigid frame 13 may be a solid bar or strip of metal or non-metallic material and the resilient member 14 may assume various other shapes and constructions to conform with different window structures and other requirements. In a special embodiment, the member 14 may be formed as a unit with the screen 15 to constitute a peripheral frame or binding for the latter and secured to the window frame 10 in any appropriate manner such as cementitiously or by clamping. In this case, the resilient screen frame 25 is formed with suitable extensions adapted to engage or press against both the sash and frame sections of the window in the manner shown and readily understood from the foregoing.

While I have shown and described a few desirable embodiments of the invention, it is understood that this disclosure is for the purpose of illustration and that various changes in shape, proportion and arrangements of parts as well as the substitution of equivalent elements and materials for those herein shown and described may be made without departing from the spirit and scope of the invention as defined in the appended claims. The specification and drawings are accordingly to be regarded in an illustrative rather than in a limiting sense.

I claim:

1. In combination with a casement type window having frame and sash sections, a screen rigidly secured to said frame section comprising a resilient frame to seal the screen perimeter, said resilient frame being adapted to cooperate with said sash section when the sash is closed to act as weather stripping for said window.

2. In combination with a casement type window having frame and sash sections, a screen of synthetic resinous material rigidly secured to said frame section, and a resilient frame to seal the perimeter of said screen and adapted to cooperate with said sash section in the closed position to provide a weather seal thereof with said frame section.

3. In combination with a casement type window having frame and sash sections, a screen, means for rigidly securing said screen to the inside of said frame section including a resilient frame for sealing the perimeter of said screen, said resilient frame cooperating with said sash section in the closed position to act as weather stripping for said window.

4. In combination with a casement type window having frame and sash sections, a screen having interwoven strands of ductile material, a screen holder comprising a rigid member secured to said frame section and a resilient member for sealing the perimeter of said screen, said resilient member cooperating with said sash section, whereby to provide a weather seal therefor.

5. In combination with a casement type win-

dow having frame and sash sections, a screen made of interwoven strands of synthetic resinous material, a screen holder comprising a rigid member secured to said frame section and a rubber member sealing the perimeter of said screen, said rubber member having a portion arranged to engage said sash section when the sash is closed to provide a weather seal therefor.

6. In combination with a casement type window having frame and sash sections, a screen, a screen holder comprising a rigid frame member and a resilient member in dovetailing connection with said frame member to hold said screen clamped between said members, said resilient member having a portion arranged to cooperate with said sash section in the closed position to act as weather stripping for said window.

7. In combination with a casement type window having frame and sash sections, a screen, 20 a screen holder comprising a rigid frame member and a resilient member in dovetailing connection therewith to seal the perimeter of said screen clamped between said members, said resilient member having extending portions arranged, respectively, to engage said frame section and to cooperate with said sash section in the closed position to act as weather stripping for said window.

8. In combination with a casement type window having frame and sash sections, a screen made of interwoven nylon strands, a screen holder comprising a rigid frame member and a rubber spline in dovetailing connection therewith to seal the perimeter of said screen clamped between said members, said rubber spline being provided with extending portions engaging said frame section and cooperating with said sash section in the closed position, whereby to act as weather stripping for said window.

40 9. In combination with a casement type window having frame and sash sections, a screen, a screen holder comprising a rigid frame member secured to said frame section and a resilient member removably secured to said rigid member to seal the perimeter of said screen clamped between said members, said resilient member being adapted to cooperate with said sash section in the closed position to act as weather stripping for said window.

50 10. In combination with a casement type window having frame and sash sections, a screen, a screen holder comprising a frame member of channel-shaped cross-section and a resilient spline clamped therein to seal the perimeter of said screen interposed between said frame member and said spline, said spline having one portion engaging said frame section and another portion adapted to engage said sash section in the closed position, whereby to act as weather stripping for said window.

60 11. In combination with a casement type window having frame and sash sections, a screen, a screen holder comprising a hollow rigid frame member and a spline of resilient material removably clamped therein to seal the perimeter of said screen interposed between said frame member and said spline, one portion of said spline engaging said frame section and another portion adapted to cooperate with said sash section, whereby to act as weather stripping for said window.

70 12. In combination with a casement type window having frame and sash sections, a screen, a screen holder comprising a rigid frame member and a resilient member, said resilient member

having one portion thereof engaging said frame section and having another portion adapted to cooperate with said sash section in the closed position, whereby to act as weather stripping for said window.

13. In combination with a casement type window having frame and sash sections, a screen

rigidly secured to said frame section and comprising resilient mounting means to seal the screen perimeter, said mounting means having a portion thereof engaging said sash section in the closed position to provide a weather seal therefor.

HARRY W. THOMAS.
